UNITED STATES PATENT OFFICE

163,917

QUILT COVER OR SIMILAR ARTICLE

Dorothy K. Wassner, New York, N. Y.

Application September 9, 1949, Serial No. 4,933

Term of patent 3½ years

(Cl. D92—2)

To all whom it may concern:

Be it known that I, Dorothy K. Wassner, a citizen of the United States of America, residing in New York city, county of New York, and State of New York, have invented a new, original, and ornamental Design for a Quilt Cover or Similar Article, of which the following is a specification, reference being had to the accompanying drawing, forming part thereof, wherein,

I claim:

The ornamental design for a quilt cover or similar article, substantially as shown.

DOROTHY K. WASSNER.
